MANIFOLDING APPARATUS

Frank Ronald Ford, Birmingham, England

Application November 9, 1935, Serial No. 49,066
In Great Britain May 29, 1934

15 Claims. (Cl. 101—132)

This invention relates to manifolding machines for use in making copies from a master sheet which bears in reversed script the matter to be reproduced, and has particular reference to machines of the type comprising a pair of rollers between which the master sheet and a moistened copy sheet may be passed in pressure contact, said master sheet being secured to one of said rollers, a stationary moistening pad, and a presser member adapted to press said copy sheet against said moistening pad.

As hitherto constructed, apparatus of the above type has proved unsuitable for rapid operation, owing to the fact that each time the presser member is allowed to descend on to a fresh copy sheet it tends to rebound or bounce away from the copy sheet and the pad momentarily, with the result that the copy sheet shows a line or narrow strip where the moistening of the paper is imperfect.

This effect is believed to be due, in the main, to the fact that the moistening pad and its container are not supported with sufficient rigidity, so that the presser member actually drops on to a support which is to some extent resilient, and one object of the present invention is to overcome the difficulty above referred to.

A second object of the invention is to provide an improved construction of the presser member aforesaid, the pressure obtained from which has hitherto been due merely to the weight of such member. The construction hereinafter described causes less friction to be applied to the copy sheet during moistening than has previously been the case, as well as permitting more even moistening of the sheet.

In machines of the type to which the invention relates, it is necessary to provide for the raising of the presser member from the moistening pad to allow successive copy sheets to be fed between the rollers. This is effected by mounting the presser member on swinging arms and arranging a cam associated with one of the rollers to engage an abutment on one of said arms at each revolution.

It is found in practice that a considerable degree of accuracy in workmanship and assembly is necessary in order that the movement of the presser member may be effected at the correct moment, having regard to the angular position of the roller associated with the cam, which roller has the master sheet clamped thereto.

A third object of the invention is to provide an improved construction of apparatus which will

not require the same precision in manufacture and assembly of the parts as hitherto.

A fourth object is to enable the master sheet to be readily and effectively secured in place upon one of the rollers, the latter being provided with a clamping member adapted to engage the sheet along the entire length of one of its edges, but which does not project above the surface of said roller. A fifth object of the invention is to provide improved operating means for the clamping member.

Further objects of the invention are to provide an improved construction of container for the moistening pad, to provide improved means whereby the pressure exerted on the other roller by the one which carries the master sheet can be equalized over the whole length of such roller, and to provide an improved means of checking the movement of the roller carrying the master sheet after each fresh copy has been taken and when the presser member aforesaid is raised.

Referring to the drawings:—

Figure 1 is a side elevation of a manifolding machine arranged in accordance with the present invention.

Figure 2 is a section on the line 2—2 of Figure 1, showing both ends of the roller which carries the master sheet.

Figure 3 is a plan view of the machine.

Figure 4 is a section on the line 4—4 of Figure 3.

Figure 5 is a sectional view of a detail shown in Figure 4.

Figure 6 is a section substantially on the line 6—6 of Figure 3.

Figure 7 is a section on the line 7—7 of Figure 6, and

Figure 8 is a section on the line 8—8 of Figure 3.

In the construction illustrated, the apparatus comprises side members 1, 1 secured together by tie-rods 2, 2 and having mounted between them a transversely disposed impression cylinder 3 to which one edge of a master sheet 4 can be clamped as hereinafter described. The spindle 5 associated with the cylinder 3 may be rotated through 40 spur gears 6, 7, 8 from a hand crank 9, or it may be operated by power means if desired.

Between the side members 1, 1 is also arranged a tank 10 holding a moistening fluid, which is fed by wicks 11 to a moistening pad 12 in a container 13. This container extends from one end of the tank 10 towards the cylinder 3, being disposed substantially tangentially in relation to the latter and terminating adjacent the surface thereof.

The pad container 13 may be an integral part

- of the tank 10, and may be formed as a shallow tray extending from the upper edge of the latter. In the construction shown, however, the top of the tank 10 is formed as a cast or other plate 5 14 which overhangs one side of the tank, this overhanging portion being recessed to constitute the pad container 13. The wicks 11, 11 are brought up through slots 15 in the top plate 14 and are suitably secured beneath the pad 12.
- 10 The operative portion of the pad 12 is that which lies immediately adjacent the outer longitudinal edge thereof, and this marginal portion may be protected by a covering 16 of thin wash leather or other suitable absorbent material.
- 15 The upper surface of the plate has mounted thereon a slidable cover member 17 and is provided with a pair of spaced guide blocks 18, 18 having straight and parallel edges which enter slots 19, 19 of corresponding form in the cover member 17. These slots are arranged at right angles to the operative longitudinal edge of the pad 12 and are longer than the guide blocks 18, 18 so that the cover member 17 can be slid to towards or away from said edge to a limited extent. For this purpose the rear edge of the cover member may be formed or provided with a handle 20.

The slots and guide blocks aforesaid are preferably so arranged that in one extreme position 30 of the cover member 17 the operative portion only of the pad 12 is uncovered to enable the copy sheets to be moistened thereon, whilst in its other extreme position the cover member almost or completely covers the upper surface of 35 the pad and thus prevents undue evaporation of the moistening fluid when the machine is out of use.

If desired, a third slot and guide block may be provided intermediate the other two and nearer 40 the pad 12, the triangular arrangement of the slots and guide blocks in such a case ensuring that the edge of the cover member 17 remains parallel to the edge of the pad 12 when said member is being slid.

45 The cover member 17 may be detachably secured to the top plate 14 by means of screws 21, 21 which screw into the guide blocks 18, 18 and normally prevent the complete removal of the cover member 17. Preferably washers 22, 22 and/or springs are engaged between the heads 50 of such screws and the upper face of the cover member 17, so that by tightening up the screws the cover member may be secured in any adjusted position.

55 When it is desired to replace or adjust the pad 12 or the wicks 11, 11, the screws 21, 21 may be removed and the cover member 17 lifted off.

After the master sheet has been secured in 60 place on the cylinder 3, the latter is rotated and copy sheets (indicated at 22) may be fed down a suitable chute 23 and passed between the cylinder and a pressure roller 24 mounted above the latter.

65 Above the moistening pad 12 is arranged a presser member extending transversely of the machine and carried by a pair of levers 25, 25 which are pivoted on pins 26, 26 secured to the side members 1, 1. The presser member may be constructed as a bar which is fixed to the ends 70 of the levers 25, 25, but preferably takes the form of a roller 27 as shown.

This roller 27 may be made of metal, or other rigid material such as vulcanite or fibre, or alternatively it may be formed of, or covered with,

a soft material such as rubber. For example, it may be provided with a rubber or other sleeve.

Means are preferably provided for adjusting the roller 27 in relation to the ends of the levers 25, 25 and in the convenient arrangement shown 5 each extremity 28 of the roller is journalled in a block 30 having an upwardly-extending stem 31 which passes through the end of the adjacent lever 25 and can be secured in its adjusted position by means of nuts 33, 33 above and below the 10 latter.

Normally the presser member rests in contact with the moistening pad 12, but is raised or moved away therefrom periodically during the operation of the machine by means of a cam 34 secured 15 to the cylinder 3. Preferably a cam 34 is secured at each end of the cylinder so that the levers 25, 25 are individually operated, and these cams may act upon rollers 35, 35 carried by members which extend downwardly from the levers 20 aforesaid. Alternatively, the cams may act on links which may be pivoted at one end to the frame of the machine and are connected at the other end to the levers 25, 25, each of these links, if desired, being provided with a roller for 25 engagement by one of the cams.

The downwardly-extending members which carry the rollers 35, 35 may comprise arms or abutments which are integral with the levers, but preferably the rollers are mounted upon the 30 ends of pins 36, 36 which extend through slots 37, 37 in the levers 25, 25, these pins having screw threaded stems and being each provided with a pair of clamping nuts 38, 38 disposed one above and one below the adjacent lever 25. By 35 employing this arrangement each roller 35 can be adjusted either in a direction which is radial to the cylinder 3, or in a direction along the length of the lever 25. The arrangement is preferably such that both such adjustments are possible. Adjustments are made by loosening the nuts 38, 38 and moving the threaded pin 36 into the correct position, after which the nuts are retightened.

By this means, the rollers 35, 35 or abutments 45 may be adjusted to compensate for any inaccuracies in the manufacture or assembly of the cams 34, 34 or of the moistening apparatus, and/or reset from time to time when the machine is in use to compensate for the effects of wear on the cams 50 or rollers, or on the bearings of the latter.

The cams 34, 34 are set so as to engage the rollers 35, 35 some time before the leading edge 55 of the master sheet comes beneath the pressure roller 24 and thus cause the presser member to be raised so that a copy sheet 22 can be passed between it and the pad 12 and can be engaged between the pressure roller 24 and the cylinder 3. The arrangement also enables the machine, when out of use, to be left with the presser mem- 60 ber held clear of the pad 12.

Means may be provided for checking the rotation of the cylinder 3 at this point, and preferably such means include a spring detent which co-operates with a disc 39 fixed to the spindle 6 of 65 the cylinder and having a notch 40 in its periphery which is engaged by the detent when the presser member is clear of the pad 12.

The detent aforesaid may comprise a pin 41 70 disposed substantially radially in relation to the disc 39 and slidably endwise in a hole in a suitable abutment provided on the machine, which abutment may be one of the tie-rods 2, 2.

The extremity of the pin 41 which lies adjacent the disc 39 may be secured to the upper end of a 75

resilient arm or bracket 42 arranged in an upright position and approximately tangentially in relation to the disc 39. The lower end of the arm or bracket may be secured to an inward projection 43 on the adjacent side member 1 of the machine.

The upper end of the arm 42 is formed with two lateral ears 44, 44 which are bent towards the disc 39 in parallel relationship, and between these ears is rotatably mounted a roller 45.

The part of the pin 41 adjacent the arm 42 is screw threaded and carries a nut 46 which forms an adjustable shoulder on the pin, a helical compression spring 47 being placed on the latter and engaged between such shoulder and the tie-rod 2 so as to press the roller 45 against the periphery of the disc 39.

When the cams 34, 34 on the cylinder 3 pass the rollers 35, 35, the levers 25, 25 are allowed to drop so that the presser member comes into contact with the copy sheet 22 and presses it against the moistening pad 12 until the cylinder 3 has completed a revolution.

Hitherto the pad container 13 has been supported only by reason of the fact that it is integral with, or attached to, one side of the tank 10, and it is thus to some extent resilient. In applying the present invention, however, an additional support is provided for stiffening the pad container 13, and this support or stiffening member may take the form of a rod 48 or bolt extending under or through the pad container and transversely of the machine, the ends of this stiffening member being carried by the side members 1, 1.

In the convenient arrangement shown, the stiffening rod 48 is of square section, and is disposed immediately beneath the pad container 13 with its ends supported in blocks or brackets 49, 49 which are secured to the inner faces of the side members 1, 1. Preferably these blocks or brackets are slotted as at 50, 50 to receive the ends of the rod 48, which are acted upon by set screws 51, 51 passing upwardly through the blocks or brackets 49, 49, adjustment of these screws enabling the stiffening rod 48 to be pressed firmly against the underside of the container 13. A lock nut 52 may be provided on each screw 51 to retain the rod 48 in its adjusted position. The pad 12 is thus rigidly supported, so that there is no tendency for the presser member to bounce after coming into contact therewith and an even pressure is exerted on the copy sheet 22 throughout the full length of the latter.

In order to provide for an adequate pressure on the copy sheet during the moistening operation, the presser member is preferably acted upon by a spring or springs. In the convenient arrangement shown, the pin 26 on which each lever 25 is mounted is formed with a shoulder 53 and a coaxial stem 54 which passes through the adjacent side member 1 and is secured by a nut 55 at the outer side of the latter. A shouldered nut 56 is secured to the inner end of each pin 26 by a set screw 57 and forms an abutment for one end 58 of a helical torsion spring 59 which is threaded on the nut 56 between the shoulder thereon and the inner face of the lever 25, the other end 60 of the spring 59 being bent outwardly to engage the lever 25. The nut 56 may be rotated on the set screw 57 and locked thereby in any angular position so that the torsion or pressure exerted by the spring 59 can be adjusted as desired.

The master sheet 4 is secured to the cylinder

3 during operation of the machine by means of a clamping device associated with the cylinder and adapted to engage one edge of the master sheet along the entire length thereof.

Preferably the cylinder 3 is formed by a casting operation and has an integral boss 61 on its interior which extends longitudinally of the cylinder parallel to the axis thereof and a tube 62 is cast into this boss so as to lie a short distance below the peripheral surface of the cylinder as 10 shown.

The cylinder is slotted longitudinally at 63, this slot extending in an inclined direction from the peripheral surface of the cylinder to the interior 15 of the tube 62 and also extending along the entire length of the cylinder parallel to the axis thereof.

Within the tube 62 is disposed a clamping rod 64 of cylindrical form and of such diameter that it can be readily oscillated within the tube about 20 its own axis.

The rod 64 is provided at one end with a head or flange 65 which abuts against one end face of the cylinder 3 when the rod is in position in the tube 62, the other end of the rod 64 being of reduced diameter and projecting from the opposite 25 end face of the cylinder. A collar 66 secured to this reduced end of the rod 64 prevents the latter from leaving the tube, whilst permitting its oscillation therewithin.

In the rod 64 is formed a groove 67 which extends longitudinally along the entire length of the rod and radially across this section of the rod to the centre of the latter. This groove 67 can be brought into or out of alignment with the slot 63 by oscillating the rod 64.

The slot 63 is of sufficient width to enable the edge of the master sheet 4 to be entered therein, but is insufficient to interfere with the operation of the cylinder 3, and since no part of the clamping device projects above the peripheral surface 40 of the latter, there is the minimum possible interference with the efficient engagement of the master sheet around the surface of the cylinder.

The oscillatory movement of the rod 64 is limited by means of a radially projecting pin 68 45 on the collar 66, which pin co-operates with stops or projections 69, 69 on the end of the cylinder 3, the groove 67 being aligned with the slot 63 in one extreme position of the rod 64 and out of alignment with said slot in the other extreme 50 position of the rod.

The rod 64 may be retained in either of its extreme positions by means of a retaining spring strip 70 anchored at one end to a screw 71 in the end of the cylinder and provided at its free end 55 with a curved portion 72 adapted to engage in one of a pair of depressions or recesses 73, 73 in the periphery of the collar 66 aforesaid.

Operating means are provided for turning the clamping rod 64 from one to the other of its extreme positions, said means including a pin 74 having at its outer end a handle 75 and at its inner end a flange 76 on which are provided a pair of diametrically opposed projections 77, 77 adapted to be engaged operatively with a pair of 65 holes or recesses 78, 78 in the collar 66.

The pin 74 is mounted in a bearing 79 in the adjacent side member 1 of the machine, this bearing having at one end a reduced screw-threaded portion 80 which is passed through a hole in the 70 side member and retained in position by a nut 81 at the outer side of the member 1.

An inwardly facing shoulder 82 is provided near the centre of the pin 74, and a helical compression spring 83 located within the reduced end 80 of the 75

bearing 79, is engaged between this shoulder and a further shoulder 84 at the inner end of the hole in the bearing. The latter is formed with a diametrical slot 85 which extends longitudinally parallel to the axis of the bearing, and in this slot 85 is engaged a cross-bar 86 which projects transversely from and is fixed to the pin 74.

When the pin 74 is in the normal or inoperative position shown, it cannot be oscillated until it has first been slidden inwardly against the action of the spring 83, so as to bring the cross-bar 86 clear of the slot 85, this endwise movement of the pin being sufficient to engage the projections 77, 77 in the holes or recesses 78, 78, provided that the clamping rod 64 is in alignment with the end of the pin 74.

In order to clamp the master sheet 4 upon the cylinder 3, the latter is rotated until the rod 64 and pin 74 are in line, after which the pin is forced inwardly until the projections 77, 77 are engaged in the holes or recesses 78, 78 as aforesaid.

The pin 74 is then turned on its own axis so as to oscillate the clamping rod 64 into a position in which the groove 67 therein is aligned with the slot 63 in the cylinder. This allows the edge of the master sheet 4 to be passed through the slot 63 into the groove 67, whereupon it may be clamped rigidly in position by oscillating the rod 64 into its other extreme position, in which the groove 67 and slot 63 are out of alignment and the sheet is engaged between their edges.

The return movement of the pin 74 necessary to clamp the master sheet aligns the cross bar 86 with the end of the slot 85, and when the handle 75 is released the spring 83 returns the operating member to its inoperative position.

The spring strip 70 retains the rod 64 in the clamping position, and the master sheet 4 is held firmly along the entire length of one edge until the clamping device is released by means of the pin 74.

An advantage of the operating means described above is that when the pin 74 has been slidden to engage the projections 77, 77 in the holes or recesses 78, 78 and the rod 64 has been turned to bring the groove 67 and slot 63 into register, the cylinder 3 is locked against rotation and cannot be moved by operating the crank 10, until the rod 64 has been returned to the clamping position and the pin 74 released.

It is thus impossible to operate the machine with the clamping device in the open position, so that there is no risk of inefficient copies being produced owing to movements of the master sheet 4 during the manifolding operation.

It is important that the pressure exerted on the cylinder 3 by the roller 24 during operation of the machine shall be equalized over the whole length of such roller, and this may be effected by providing separate springs which act transversely at opposite ends of the spindle 87 on which the roller is mounted so as to press the latter against the cylinder 3, separate screw-operated means being also provided for increasing or decreasing the compression or tension of each spring, whereby the pressure exerted at one end of the roller 24 may be adjusted independently of the other end.

The ends of the spindle 87 of the roller 24 engage in bearings 88, 88 which are mounted in suitable guide channels 89, 89, so that they can slide towards or away from the axis of the cylinder 3.

To each of said bearings 88, 88 is pivoted one

end of a downwardly extending rod 90, the lower end of which is screw-threaded at 91 and passes through a crank pin 92 associated with a crank arm 93 on a rock shaft 94 extending transversely of the machine. The free end of each crank arm 93 may be forked to accommodate the threaded end 91 of the rod 90, which passes with clearance through a diametral hole in the crank pin 92, the latter being rotatably supported at its ends in the forked end of the crank arm.

A helical compression spring 95 is placed on the end of each rod 90 below the crank pin 92 and is engaged between the latter and a washer 96 which is held in place by an adjusting nut 97.

A flat or flats may be formed on the screw-threaded portion 91 of each rod 90 as at 98 and the aperture in each washer 96 may be made of suitable non-circular section so that it cannot rotate when being adjusted along the length of the rod 90 by the nut 97. The coacting faces of the washer 96 and nut 97 may be provided with interengaging serrations and recesses as at 99, so that the nut is retained frictionally in its adjusted position.

It will be seen that the springs 95, 95 act to draw the roller 24 down against the cylinder, and the separate adjusting means provided enable the spring pressures acting on opposite ends of the roller 24 to be adjusted independently.

The rock shaft 94 may have attached thereto, at the side opposite to the crank arms 93, 93, an operating lever 100 having its free end bent laterally so as to project through an arcuate slot 101 in the adjacent side member 1 of the machine.

During the manifolding operation this lever 100 is supported near the upper end of the slot 101 by means of an inwardly-projecting stop peg 102 which engages beneath it. In this position of the operating lever the bearings 88, 88 are held down by the crank arms 93, 93 and rods 90, 90, so that the roller 24 as a whole is forced resiliently against the cylinder 3 with a pressure dependent on the amount to which the springs 95, 95 are compressed. The stop peg 102 is mounted eccentrically on an oscillatable disc 103 having a stem 104 which extends through the side member 1 of the machine and is provided externally thereof with a knob or handle 105. Rotation of this knob 105 alters the position of the eccentric stop peg 102, the angular position of the lever 100, and hence the pressure exerted by the roller 24 when in its operative position, being thus adjusted.

In order that the roller 24 may be raised from the cylinder 3 to facilitate the operation of clamping the master sheet 4 to the latter, the lever 100 is made flexible in a transverse direction and is thus capable of being bent inwards to clear the end of the stop peg 102 when pressure is applied to its free end, which latter may carry a suitable button or knob 106. A tension spring 107, assisted by the main springs 95, 95, acts to move the lever 100 towards the lower end of the slot 101 upon release from the stop peg 102, and in consequence the crank arms 93, 93 move upwardly. This brings each crank pin 92 into engagement with the lower end of an abutment nut 108 of sleeve-like form which is screwed on the rod 90 above the crank pin and which can be adjusted longitudinally of said rod. A lock-nut 109 retains each abutment nut 108 in its adjusted position.

What I claim then is:—

1. A manifolding machine comprising a stationary frame, a pair of rollers between which a

master sheet and a moistened copy sheet may be passed in pressure contact, a stationary moistening pad, a presser member adapted to press said copy sheet against said moistening pad, a container for said pad, an inherently rigid rod disposed transversely of said frame, slotted brackets on the sides of said frame which receive the ends of said rod, and set screws engaging in said bracket and adjustable to force said rod against the underside of said pad container.

2. A manifolding machine comprising a pair of rollers between which a master sheet and a moistened copy sheet may be passed in pressure contact, a stationary moistening pad, a presser member adapted to press said copy sheet against said moistening pad, swinging arms carrying said presser member, a torsion spring acting on said arms to press said presser member against said copy sheet and pad, a nut attached to one end of said spring and rotatable to adjust the torsion exerted thereby, and means for locking said nut angularly.

3. A manifolding machine comprising a pair of rollers between which a master sheet and a moistened copy sheet may be passed in pressure contact, a stationary moistening pad, a presser member adapted to press said copy sheet against said moistening pad, swinging arms carrying said presser member, a cam associated with one of said rollers, an abutment on one of said arms which is engaged by said cam for effecting periodical raising of said presser member to allow insertion of fresh copy sheets, a threaded stem on said abutment extending through a longitudinal slot in said arm, and clamping nuts provided on said stem above and below said arm to allow the length of said abutment to be adjusted.

4. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or moved to a further position in which said groove and slot are out of register so as to clamp said master sheet, and a pin mounted on said stationary frame opposite to the end of the roller carrying said master sheet, said pin being movable endwise to engage said clamping member and turnable to operate same.

5. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or moved to a further position in which said groove and slot are out of register so as to clamp said

master sheet, a pin mounted on said stationary frame opposite to the end of the roller carrying said master sheet, said pin being movable endwise to engage said clamping member and turnable to operate same, and means for preventing turning movement of said pin except when in operative engagement with said clamping member.

6. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or moved to a further position in which said groove and slot are out of register so as to clamp said master sheet, a pin mounted on said stationary frame opposite to the end of the roller carrying said master sheet, said pin being movable endwise to engage said clamping member and turnable to operate same, means for preventing turning movement of said pin except when in operative engagement with said clamping member, and means for preventing said pin from return endwise movement of said pin after said clamping member has been opened thereby until said member has been turned to its closed position.

7. A manifolding machine comprising a pair of rollers between which a master sheet and a moistened copy sheet may be passed in pressure contact, one of said rollers being formed with a longitudinal recess which is spaced from the peripheral surface of said roller and connected thereto by a slot, a tube fixed within said recess and having a slot in permanent alignment with the slot in said roller and a cylindrical clamping member fitting closely in said tube and extending substantially the whole length of said roller, said clamping member having a longitudinal groove therein and being turnable about an axis parallel to its length, whereby said groove may be aligned with said slot to allow insertion of one edge or end of said master sheet therein and moved to a further position in which said groove is out of register with said slot so that said master sheet is nipped between one inner edge of the slot in said tube and one edge of said groove.

8. A manifolding machine comprising a pair of rollers between which a master sheet and a moistened copy sheet may be passed in pressure contact, a tube cast into one of said rollers at a short distance below the peripheral surface thereof, said tube having a longitudinal slot therein and being arranged parallel to the axis of said roller, said last-mentioned roller having a longitudinal slot therein which extends in an inclined direction from the peripheral surface of said roller to the interior of said tube and is in permanent alignment with the slot in the latter, and a cylindrical clamping member fitting closely in said tube and extending substantially the whole length of said roller, said clamping member having a longitudinal groove therein and being turnable about an axis parallel to its length, whereby said groove may be aligned with said slot to allow insertion of one edge or end of said

- master sheet therein and subsequently moved to a further position in which said groove is out of register with said slots so that said master sheet is nipped between one inner edge of the slot in 5 said tube and one edge of said groove.
9. A manifolding machine comprising a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or may be moved to a further position in which said groove and slot are out of register so that said master sheet is nipped between one inner edge of said slot and one edge of said groove, flanges or collars provided on said clamping member and engaging the end faces of 20 said roller, co-operating stop means provided on one of said flanges or collars and on the adjacent end face of said roller to limit movement of said clamping member between its open and closed positions, and a spring detent adapted to 25 retain said clamping member in either of said positions.
10. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or may be moved to a further position in which said groove and slot are out of register so as to clamp said master 30 sheet, flanges or collars provided on said clamping member and engaging the end faces of said roller, a pin mounted on said stationary frame opposite to the end of the roller carrying said master sheet, said pin being movable endwise and turnable in said bearing, a head provided at one end of said pin, and a pair of diametrically opposed projections on said head, one of the flanges or collars on said clamping member having a pair of diametrically opposed holes or recesses therein, and said projections being adapted to engage operatively with said holes or recesses on endwise movement of said pin, said clamping member being operated by a turning movement of 35 said pin.
11. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or may be moved to a further position in which said groove and slot are out of register so as to clamp said master sheet, a pin mounted on said stationary frame opposite to the end of the roller carrying said

master sheet, a bearing for said pin in said frame, said bearing being formed with a slot which extends parallel to its axis, said pin being movable endwise and turnable in said bearing, projections at one end of said pin adapted to engage operatively with the adjacent end of said clamping member on endwise movement of said pin, said clamping member being operable by a turning movement of said pin, and a cross-bar fixed to said pin and engaging in the slot in said bearing so as to prevent said pin from being turned during its endwise movement until said projections are in operative engagement with said clamping member. 5

12. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or may be moved to a further position in which said groove and slot are out of register so as to clamp said master 20 sheet, flanges or collars provided on said clamping member and engaging the end faces of said roller, a pin mounted on said stationary frame opposite to the end of the roller carrying said master sheet, said pin being movable endwise and turnable in said bearing, a head provided at one end of said pin, and a pair of diametrically opposed projections on said head, one of the flanges or collars on said clamping member having a pair of diametrically opposed holes or recesses therein, and said projections being adapted to engage operatively with said holes or recesses on endwise movement of said pin, said clamping member being operated by a turning movement of 25 said pin.

13. A manifolding machine comprising a stationary frame, a pair of rollers between which a master sheet and a moistened copy sheet may be passed in pressure contact, one of said rollers being formed with a longitudinal recess which is spaced from the peripheral surface of said roller and connected thereto by a slot, a clamping member mounted in said recess and extending substantially the whole length of said roller, said clamping member having a longitudinal groove therein and being turnable about an axis parallel to its length, whereby said groove may be aligned with said slot to allow insertion of one edge or end of said master sheet therein or may be moved to a further position in which said groove and slot are out of register so as to clamp said master sheet, a pin mounted on said stationary frame opposite to the end of the roller carrying said master sheet, a bearing for said pin in said frame, said bearing being formed with a slot which extends parallel to its axis said pin being movable endwise and turnable in said bearing, projections at one end of said pin adapted to engage operatively with the adjacent end of said clamping member on endwise movement of said pin, said clamping member being operable by turning movement of said pin, a cross-bar fixed to said pin and engaging in the slot in said bearing so as to prevent said pin from being turned during its endwise move- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ment until said projections are in operative engagement with said clamping member, and spring means adapted to return said pin to its inoperative position when said cross-bar is in alignment 5 with the slot in said bearing.

14. A manifolding machine comprising a stationary frame, a pair of rollers between which a master sheet and a moistened copy sheet may be passed, a spindle projecting at opposite ends of 10 one of said rollers, separate helical compression springs acting transversely upon opposite ends of said spindle to press said roller against the other roller of said pair, means provided on said other roller for clamping said master sheet thereto, 15 bearings for said roller spindle mounted on said frame for sliding movement towards or away from said other roller, an oscillatable shaft carried by said frame, crank arms or their equivalent fixed on said shaft, crank pins provided on said 20 crank arms and each having a transverse hole therein, separate screw-threaded rods pivoted to said bearings and passing with clearance through the holes in said crank pins, nuts screwed on said rods and adapted to be locked longitudinally 25 thereof, said nuts being engaged by said crank pins when said rods are moved to separate said rollers, washers slidable on said rods but pre-

vented from rotating relatively thereto, said helical springs being placed over said rods and engaged between said crank pins and said washers, adjusting nuts screwed on to said rods to retain said washers and rotatable to vary the compression of individual springs, and means for locking said adjusting nuts in their adjusted position. 5

15. A manifolding machine comprising a stationary frame, a pair of rollers between which a master sheet and a moistened copy sheet may be 10 passed a disc having a notch in its periphery and rotatable with one of said rollers having means for clamping said master sheet thereto, an abutment on said frame, a shouldered pin disposed substantially radially of said disc and slidable 15 endwise in said abutment, a helical compression spring carried on said pin and engaged between the shoulder thereon and said abutment so as to urge said pin towards the periphery of said disc, a roller carried by the end of said pin and adapted 20 to engage the periphery of said disc, and a spring arm or bracket attached to said frame and supporting said pin adjacent the roller carried thereby, said arm or bracket being disposed approximately tangentially to said disc. 25
